(57) **CLAIM**

The ornamental design for a lighter, as shown and described.

DESCRIPTION

FIG. 1 is a perspective view of the lighter in accordance with the present invention;

FIG. 2 is a perspective view of the lighter of FIG. 1 showing the punch cutter portion of the lighter in an alternate configuration for clarity of disclosure thereof;

FIG. 3 is a top plan view of the lighter of FIG. 1;

FIG. 4 is a bottom plan view of the lighter of FIG. 1;

FIG. 5 is a front elevation of the lighter of FIG. 1;

FIG. 6 is a rear elevation of the lighter of FIG. 1;

FIG. 7 is a right side elevation of the lighter of FIG. 1; and,

FIG. 8 is a left side elevation of the lighter of FIG. 1.

The broken lines in the drawings depict parts of the lighter that form no part of the claimed design.
